UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

EXCAVATING-MACHINE.

1,159,173.

Specification of Letters Patent.

Patented Nov. 2, 1915.

Application filed September 2, 1908. Serial No. 451,297.

To all whom it may concern:

Be it known that I, MORTON G. BUNNELL, a citizen of the United States of America, and resident of Chicago, Cook county, Illinois, have invented a certain new and useful Improvement in Excavating-Machines, of which the following is a specification.

My invention relates to excavating machinery in general, but more particularly 10 to machines for making ditches or trenches.

Generally stated, therefore, the object of my invention is the provision of an improved excavating and ditching machine.

A special object is the provision of a machine 15 adapted more particularly for making ditches or trenches on a hill-side, which obviously involves some problems and difficulties not true of ordinary work on a level stretch of ground.

Another object is the provision of a machine 20 which will not only work on a hill-side, but which will also deposit all of the dirt at the lower side thereof, whereby the lower side of the ditch will be given an embankment sufficient to insure a ditch or 25 trench of the desired depth and capacity.

A further object is to provide a machine 30 of this kind that may be reversed to throw the dirt either to the right or the left, thus making it possible to work from a hill sloping in one direction to a hill sloping in the opposite direction, without turning the machine around.

To the foregoing and other useful ends, 35 my invention consists in matters hereinafter set forth and claimed.

In the accompanying drawings Figure 1 is a rear elevation of an excavating machine embodying the principles of my invention, 40 showing the method of using the same for hill-side work. Fig. 2 is a side elevation of said machine, partly in section, the section being taken on line 2—2 in Fig. 1, looking in the direction indicated by the arrows, showing 45 the method by which the machine cuts or works down into the hill-side to the desired depth, advancing step by step and throwing all the dirt down hill, thus forming an embankment on the down-hill side of the ditch, 50 as shown in Fig. 1.

As thus illustrated, my invention comprises a suitable body A mounted on trucks B of any suitable, known or approved char-

acter. At its forward end the said body is provided with an upright frame C 55 provided at its upper end with sheaves c. A vertically sliding frame D is supported and guided in its up and down movements by the frame C, and provided with sheaves d, which latter are preferably set with their 60 common axis of rotation extending horizontally at right angles to the separate and parallel axes of the sheaves c. The frame D is provided below with sprocket wheels d', and at its upper end with rolls d''. Said 65 sprocket wheels have axles or journals upon which are mounted the lower ends of the run-ways E and E', which are of any suitable form, and which are held in their inclined positions by stay rods e and e'. 70 Sprocket wheels F and F' are mounted respectively on the upper ends of the run-ways E and E', which latter project upwardly and outwardly from the opposite sides of the movable frame D, it being observed that 75 the run-way E' is preferably longer than the other. An endless link belt G is trained over the sprockets F and F' and under the sprockets d"—d', and is provided on its face or outer side with cutters g which act on the 80 face of the cut to give clearance for the belt, as shown in Fig. 2. Said belt is also provided with blades g' that are so disposed thereon as to enable them collectively to operate on the ground for the full width of 85 the belt, although each blade is narrower than the belt. Sufficient slack is provided in the belt to enable the same to rest on the rolls d"—d', the lower outer portions of the chain being held down to its work by the 90 run-ways E and E', and at its middle by the lower cross run-way H that connects the two sides of the frame D. It will also be seen that the frame C has side members that serve as guides for the frame D, and that 95 have lower end portions c' that reach down below the body A sufficiently to enable the excavating belt to fall to the level of the bottom of the ditch, as shown in Fig. 2. A pair of frames I, one at each side of the machine, connects the end frame C with the rear of the body A, thus insuring a strong 100 and rigid structure for holding the excavating belt and its supporting frame in an upright position.

Sheaves J are provided on the floor of the

body A, and a hoisting and lowering cable K is arranged to run on all of said sheaves, said cable being connected with the drum k operated at the rear of the body of the engine k'. At one side of the machine the sprocket wheel d' has its journal or shaft provided with a gear wheel L that meshes with a pinion l on a shaft l' journaled in bearings on the frame D. This gearing constitutes a means for operating the belt while it is moving bodily downward. A tumbling rod M connects the shaft l' with suitable gearing m operated by said engine, said rod having the usual telescoping connection m' permitting the frame D to move up and down, whereby the requisite power is transmitted from the engine to run the excavating belt while the latter is slowly settling or moving down. Of course, though, any suitable or well known operating connection may be employed for driving the belt. A boiler N disposed on the rear end of the body A furnishes the stream for the said engine.

In operation, the excavating belt is hoisted by the cable K and then allowed to rest on the ground with the run-way E extending down hill and the run-way E' extending up hill. The belt is then driven in the direction of the arrows, with the result that the dirt is torn up and conveyed across the path of travel of the machine to the down-hill side and there discharged to make an embankment for the lower side of the ditch. As shown in Fig. 1, the belt is working downward, and will continue to do so until it reaches the line X, which latter represents the outline of the ditch in cross section, while the line Y represents the slope or incline of the hill side upon which the machine is working. As soon as the excavator belt has cut its way down to the level of the floor or bottom of the ditch, then the belt is hoisted above the ground, the machine is moved forward a distance equal to the width of the belt, and then the latter is again started on its downward course. Thus the ditch is made by a step-by-step movement of the machine in the direction desired therefor, the two banks being flaring in cross section, and the greater length of the belt on the up-hill side insuring a bank that is smooth and sloping from top to bottom. The run-ways E and E' and the supports e and e' are made adjustable, as by adding or taking out sections thereof, so that the longer run-way can be made shorter and the shorter run-way made longer, thus reversing the conditions shown in the drawings. The belt G can then be taken off and reversed, so as to carry the dirt in the opposite direction. With this provision, therefore, the machine can be reversed to throw the dirt to the opposite side,

depending on the requirements of the work. 65 For example, when the machine passes from one hill side to another having the opposite slope, then the dirt must be thrown to the other side of the machine, and this can be accomplished in the manner explained. 70 Thus the machine can work ahead from hill-side to hill-side without the necessity of turning around whenever it passes from one extending upward at the right to one extending upward at the left. And in this 75 way side-hill ditching is accomplished with a considerable saving of time and money.

What I claim as my invention is:—

1. An excavating machine for making ditches on hill sides, comprising an endless 80 series of digging buckets extending transversely of the ditch, runways on which said buckets travel, disposed in position to form a ditch with flat bottom and sloping sides, means for bodily raising and lowering said 85 runways and series of buckets, to form the ditch by a succession of downward cuts, a body having said means supported on its forward end, means for continuously operating said buckets from the upper to the lower 90 side of the ditch, to form a spoil bank at the lower side of the ditch, and means whereby said body travels on the bottom of the ditch in rear of said buckets, each bucket discharging at the lower side of the ditch the 95 dirt carried from the upper side thereof.

2. An excavating machine for making ditches on hill sides, comprising an endless 100 series of digging buckets extending transversely of the ditch, runways on which said buckets travel, disposed in position to form a ditch with flat bottom and sloping sides, means for bodily raising and lowering said 105 runways and series of buckets, to form the ditch by a succession of downward cuts, a body having said means supported on its forward end, means for continuously operating said buckets from the upper to the lower side of the ditch, to form a spoil bank at the lower side of the ditch, and means whereby said body travels on the bottom of the ditch in rear of said buckets, each bucket discharging at the lower side of the ditch the 110 dirt carried from the upper side thereof, the runway at the upper being longer than 115 the one at the lower side.

3. An excavating machine for making ditches on hill sides, comprising an endless 120 series of digging buckets extending transversely of the ditch, runways on which said buckets travel, disposed in position to form a ditch with flat bottom and sloping sides, means for bodily raising and lowering said 125 runways and series of buckets, to form the ditch by a succession of downward cuts, a body having said means supported on its forward end, means for continuously operating said buckets from the upper to the lower

side of the ditch, to form a spoil bank at the lower side of the ditch, and means whereby said body travels on the bottom of the ditch in rear of said buckets, each bucket discharging at the lower side of the ditch the dirt carried from the upper side thereof, said runways having sprocket wheels for said series of buckets, means for driving one of said wheels to operate said buckets hav-

ing provision for permitting said up and down movement of the runways and buckets.

Signed by me at Chicago, Illinois, this 22nd day of August 1908.

MORTON G. BUNNELL.
